Primary Examiner—Cathron Brooks*Assistant Examiner*—Linda Brooks(74) *Attorney, Agent, or Firm*—Volpe and Koenig P.C.(57) **CLAIM**

The ornamental design for a bottle cage, as shown and described.

DESCRIPTION

FIG. 1 is a perspective view of a first embodiment of the bottle cage according to the present invention;

FIG. 2 is a front elevational view of the bottle cage of FIG. 1;

FIG. 3 is a rear elevational view of the bottle cage of FIG. 1;

FIG. 4 is a right elevational view of the bottle cage of FIG. 1, the left elevational view being a mirror image thereof;

FIG. 5 is a top plan view of the bottle cage of FIG. 1;

FIG. 6 is a bottom plan view of the bottle cage of FIG. 1;

FIG. 7 is a perspective view of a second embodiment of the bottle cage according to the present invention;

FIG. 8 is a front elevational view of the bottle cage of FIG. 7;

FIG. 9 is a rear elevational view of the bottle cage of FIG. 7;

FIG. 10 is a right elevational view of the bottle cage of FIG. 10, the left elevational view being a mirror image thereof;

FIG. 11 is a top plan view of the bottle cage of FIG. 7; and,

FIG. 12 is a bottom plan view of the bottle cage of FIG. 7.

All broken-lines appearing in the drawings are for illustrative purposes only and form no part of the claimed design.

1 Claim, 6 Drawing Sheets
